UNITED STATES PATENT OFFICE.

HARVEY EAGON, OF NEW COMERSTOWN, OHIO.

COMBINED WINDOW-SCREEN AND WEATHER-STRIP.

SPECIFICATION forming part of Letters Patent No. 783,936, dated February 28, 1905.

Application filed June 20, 1904. Serial No. 213,357.

To all whom it may concern:

Be it known that I, HARVEY EAGON, a citizen of the United States, residing at New Comerstown, in the county of Tuscarawas and 5 State of Ohio, have invented certain new and useful Improvements in a Combined Window-Screen and Weather-Strip; and I do declare the following to be a full, clear, and exact description of the invention, such as will enable others skilled in the art to which it appertains to make and use the same.

This invention relates to improvements in a combined window-screen and weather-strip.

The object of the invention is to provide a 15 device of this character whereby when the window is closed an air and water tight joint will be formed at the lower edge of the same and when said window is raised the screen will be unreeled by the same, thereby covering 20 the opening.

A further object is to provide a device of this character which will be simple in construction, strong, durable, and efficient, and which when the window is closed will securely 25 clamp and prevent the same from rattling.

With these and other objects in view the invention consists of certain novel features of construction, combination, and arrangement of parts, as will be hereinafter more fully described, and particularly pointed out in the appended claim.

In the accompanying drawings, Figure 1 is a front elevation of a window, showing the application of the invention thereto, the parts being broken away and the window shown open. Fig. 2 is a vertical sectional view through a window having the device applied thereto and showing the sash in closed position. Fig. 3 is a similar view showing the 35 sash raised and the screen covering the opening; and Fig. 4 is a horizontal sectional view of one side of the window frame and sash, taken above the screen-casing.

Referring more particularly to the drawings, 1 denotes the window-frame. 2 denotes the sash. 3 denotes the outer sill of the window. Journalized in the sides of the window-frame near said outer sill and adjacent to the lower cross-piece 4 of the sash is a spring- 45 roller 5, on which is adapted to be wound a

flexible screen 6, which may be of any suitable material, but which is preferably constructed of fine-mesh linen fabric. The outer edge of said screen is secured to the lower edge of the cross-piece 4 of the sash by means of a suitable attaching-strip 7, so that when said sash is raised the screen will be unreeled and drawn upwardly by the sash, thus covering the window-opening. The attaching-strip 7 has a rounded upper corner, over which the 55 screen 6 extends.

The laterally-curved spring-metal casing 8 is secured to the outer sill 3 and is adapted to cover and protect the screen 6 when the sash is lowered and the screen wound upon the 65 spring-roller 5. The casing 8 is secured to the sill 3 at its lower outer edge by means of a laterally-projecting flange 9, which is screwed down upon said sill. The upper inner edge of the casing 8 is formed with a bead 10, which is 70 adapted to engage the outer face of the lower sash-strip 4 when the same is in closed position. A downwardly-curved cap-strip 12 is secured to said outer face of the sash-strip 4, and when said sash is lowered is adapted to 75 engage the beaded edge of the casing 8, thereby forcing the same into tight engagement with said sash-strip, thus holding the sash against movement or rattling. The cap-strip 12 also forms a covering for the joint between 80 the beaded edge of the casing and the sash-strip 4, thereby preventing water or air from entering said joint, thus forming a perfect weather-strip and antirattling device for said sash, as well as a protective casing for the 85 screen.

As hereinbefore stated, when the window-sash is raised the screen will be thereby unreeled and raised, thus covering the window-opening and preventing access of insects, &c. 90 When the sash is lowered, the spring-roller will automatically wind the screen up within the casing 8.

A screen constructed and arranged as herein shown and described will be found to be 95 convenient and efficient and always in place and ready for use, thereby avoiding the annoyance of removing and replacing a screen, as in the case of the ordinary frame-screen commonly used.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus described my invention, what I claim, and desire to secure by Letters Patent, is—

The herein - described combined window-screen and weather - strip, consisting of a spring-roller, rotatably mounted in a window-frame, a flexible screen, adapted to be wound and unwound about said roller, an attaching-strip having a rounded upper corner for attaching the outer end of said screen to the bottom of the lower cross-piece of the window-sash, whereby when said sash is raised, said screen will be unwound and raised in the

vertical plane of the outer surface of the sash, a laterally-curved spring-metal protective casing and antirattler secured at its lower edge to the outside window-sill, a bead formed on the upper edge of said casing to bear against the outer side of the lower cross-piece of the sash, a downwardly-curved cap-strip secured to the lower cross-piece of said sash, whereby, when said sash is lowered, said cap-strip will engage and cover the beaded edge of said protective casing and force said beaded edge into tight engagement with said lower cross-piece of the sash, holding the latter against rattling and forming an air and water tight joint as well as a covering for said screen-roller, essentially as described.

In testimony whereof I have hereunto set my hand in presence of two subscribing witnesses.

HARVEY EAGON.
